UNITED STATES PATENT OFFICE.

BETHUEL M. DAVIS, OF CHICAGO, ILLINOIS.

DESIGN FOR A CASE OR CABINET FOR AUTOMATIC VENDING-MACHINES.

SPECIFICATION forming part of Design No. 35,296, dated November 19, 1901.

Application filed October 26, 1901. Serial No. 80,150. Term of patent 3½ years.

To all whom it may concern:

Be it known that I, BETHUEL M. DAVIS, a citizen of the United States, residing at Chicago, in the county of Cook and State of Illinois, have invented and produced a new and original Design for a Case or Cabinet for Automatic Vending-Machines, of which the following, in connection with the accompanying drawing, is a full, clear, and exact specification.

The said drawing is a perspective view of a case or cabinet for automatic vending-machines embodying my design.

The leading features of my design consist of a case or cabinet for automatic vending-machines having the angular base A, surrounded by the open frame, comprising standards B and top C.

On the front and lower part of the base A is a horizontal pan-shaped portion D, immediately over which are located two outwardly-projecting flat members E, which are arranged in vertical parallel planes a short distance apart and at opposite sides of an inclined web F, extending downwardly toward the pan D, the parts E F being apparently formed on and carried by the front wall of the base A. Immediately above the members E, whose outer edges are curved upwardly and inwardly from their lower straight edges, is an offset tablet-shaped enlargement G, whose upper end is curved or rounded and surrounded by a block H, upon which is a rounded slotted projection I, while its lower end appears to be supported upon a base J, extending laterally in the form of two wings whose lower edges converge to a point K immediately over the incline F.

The upper outer face of the tablet portion G is arched over with beading L, framing a lion's head or face M, while the lower end

and corners are bordered by beading M of similar design, which is also carried around the edges of the base J of the tablet.

The base A of the cabinet is of pyramidal form, rising from a pedestal O, which is curved outwardly a slight distance therefrom, and the point of juncture between the pedestal and base is marked with a line of beading P, as is also the point of juncture between the upper edge of the base and the open frame B C.

The corner posts or legs B of the open frame rise perpendicularly from the corners of the base A, constituting an inclosure or cubical formation, and each of which posts B is faced with beading Q, comprising alternate long and short sections.

The top of the base A in the space inclosed by the corner posts or legs B is inclined on all four sides toward a central bottom portion R, and above this on the upper ends of the posts B appears the top or cover C, whose upper surface is rounded upwardly on all four sides, as shown at S, to a central four-sided peak T.

The edge of the cover C is fringed by a corrugated border U, and within the rectangular frame constituted by the edges of the cover C, the uprights or posts B, and the upper rows of beading P are located beveled glasses V.

Having thus described my invention, what I claim as new therein, and desire to secure by Letters Patent, is—

The design for a case or cabinet for automatic vending-machines, substantially as herein shown and described.

BETHUEL M. DAVIS.
